United States Patent Office

Des. 232,091

Patented July 16, 1974

232,091

NON-CLOG GUTTER OR SIMILAR ARTICLE

John Clark, 808 Southgate, McHenry, Ill. 60050

Filed Aug. 31, 1972, Ser. No. 285,226

Term of patent 14 years

Int. Cl. D23—01

U.S. Cl. D23—45

FIG. 1 is a fragmentary perspective view of a non-clog gutter or similar article, showing my new design;

FIG. 2 is an end elevational view thereof;

FIG. 3 is a fragmentary front elevational view thereof;

FIG. 4 is a fragmentary top plan view thereof; and

FIG. 5 is a fragmentary bottom plan view thereof.

I claim:

The ornamental design of a non-clog gutter or similar article, as shown.
